Dec. 1115

William W. Wilson, of Pittsburgh, Pa.
Letters Patent No. 1115. Dated July 5, 1851.

The Schedule referred to in these Letters Patent and making part of the same.

Be it Known,

That I, Wm. W. Wilson aforesaid have invented or produced a new and original design for a Sun Dial, and do hereby declare that the following is a full and exact description of the same - reference being had to the drawing accompanying and to the letters of reference marked thereon, viz.:

a, a', Represents Equation of Time Tables.

b, Is a mirror and around it are represented the points of the compass.

c, c', c'', c''', Is a complete representation of the Design.

Claim.

What I claim and desire to secure by letters patent of the United States is the new and improved configuration of Sun Dials as set forth in the Specification and accompanying drawing.
